UNITED STATES PATENT OFFICE.

CHARLES E. SCRIBNER, OF CHICAGO, ILLINOIS, ASSIGNOR TO THE WESTERN ELECTRIC COMPANY, OF SAME PLACE.

CONDENSER AND TEST-CIRCUIT FOR MULTIPLE SWITCH-BOARDS.

SPECIFICATION forming part of Letters Patent No. 292,865, dated February 5, 1884.

Application filed June 11, 1883. (No model.)

To all whom it may concern:

Be it known that I, CHARLES E. SCRIBNER, a citizen of the United States, residing at Chicago, in the county of Cook and State of Illinois, have invented a certain new and useful Improvement in Condensers and Test-Circuits for Multiple Switch-Boards, of which the following is a full, clear, concise, and exact description, reference being had to the accompanying drawings, forming a part of this specification.

My invention herein relates to condensers and test-circuits for multiple switch-boards of a telephone-exchange; and it consists of a condenser placed in the circuit of the different pairs of connecting-cords and testing apparatus at the different boards and circuits, as herein described and claimed.

In the drawings, which are illustrative of my invention, Figure 1 is a diagram of two telephone-lines connecting with three multiple switch-boards and a pair of connecting-cords, including a condenser and testing apparatus at each board. The operator's outfit—consisting of the usual telephone, transmitter, generator or calling battery, and bell—is not shown, its construction and use being too well known to require description. Fig. 2 is a detailed view of the loop-plug which I use with my testing apparatus. Fig. 3 is a detailed view of my plug for terminals of the pairs of conducting-cords. The shank of the plug, with the exception of the point, is provided with a rubber sleeve, which insulates the plug from the frame of switch. The insulating material being removed from the portion of the point which comes against the spring of the switch, contact is closed between the plug-point and the spring when the plug is inserted.

The circuit of telephone-line 1 may be traced from the subscriber's office to the spring *a* of the switch upon board A, thence through the contact-point of said switch to a switch upon board B, and so on to the last board, and through an annunciator to ground. When two lines are connected, as shown at board B, by inserting the terminal plugs of a pair of conducting-cords into the switches, as shown, the lines will be disconnected from the last board or succeeding boards. Lines thus con-

nected are open at the condenser *b* to battery-currents, but closed to voice-currents, since, as is well known, voice-currents are readily transmitted through a condenser. Suppose, 55 now, line 2 should be asked for at board A. The operator, by inserting loop-plug *c* in switch *d* of said line, loops into the circuit of the two lines the bell *e* and battery *f* of his testing apparatus. Since the lines, when connected, are open to battery-currents at the condenser *b*, no current will be sent through the bell *e* from battery *f*. The bell, therefore, not ringing, the switchman at board A will know that line 2 is in use.

The clearing-out annunciator in the circuit with a condenser may be operated by reversed currents sent by a magneto-generator.

Since lines in use on one board are cut off from all succeeding boards, it is obvious that 70 it is unnecessary to make the preliminary test at the last board to ascertain whether a line called for is in use. If the line is found open when the calling-battery is thrown upon it, the operator will know that the line is in use 75 at some one of the preceding boards, and, the line being open, there will be no danger of confusion arising from connections made at any board succeeding the one where the line is connected with another.

The batteries in the test-circuits at the different boards should not be of sufficient force to throw down the individual annunciator in a line. I introduce sufficient resistance into the bells of the different test-circuits, so that 85 there may be no danger of trouble from the current sent to line from a testing-battery when no condenser is included in its circuit—that is, when the line is not in use.

I claim—

1. The combination, in a multiple system of switch-boards, of pairs of conducting-cords and condensers, a condenser being in the circuit of each pair of cords, and testing apparatus at the different boards, substantially as 95 specified.

2. A switch provided with a frame and spring, said spring being insulated from the frame, a contact-point or lug upon said frame, upon which said spring normally rests, and a connecting-plug provided with insulating material, said plug being adapted to be inserted

in said switch, whereby said spring is lifted from said lug or contact-point and connected to the point of the plug, substantially as and for the purpose specified.

5 3. The combination, with two connected telephone-lines, with a condenser in circuit at the central office, of a testing-circuit containing a battery and signaling device adapted to be looped into the circuit of the connected

telephone-lines, substantially as and for the purpose specified.

In witness whereof I hereunto subscribe my name this 7th day of June, A. D. 1883.

CHARLES E. SCRIBNER.
